UNITED STATES PATENT OFFICE

FRANK R. ZUMBRO, OF WAYNESBORO, PENNSYLVANIA, ASSIGNOR TO FRICK COMPANY,
OF WAYNESBORO, PENNSYLVANIA, A CORPORATION OF PENNSYLVANIA

LIQUID COOLER

Application filed January 19, 1929. Serial No. 333,559.

This invention relates to cooling units designed primarily for cooling liquid and having a particular utility in cooling and drying liquid carbon dioxide preparatory to its admission for expansion to a carbon dioxide snow machine.

An object of the invention is to provide a cooling device which will be adapted to cool the fluid which passes through it to a very low temperature and to do this with the maximum of efficiency.

A further object is to provide a cooling device in which the cooled fluid may pass without danger of freezing in the cooler and thereby clogging the fluid conduits in the device.

A further object is to provide a device for cooling carbon dioxide which will remove water ice from the carbon dioxide.

A further object is to provide a device for drying a fluid by freezing out the water from the fluid.

Referring to the accompanying drawing which is made a part hereof and on which similar reference characters indicate similar parts,

The figure is a longitudinal sectional view of the cooler.

In the drawing numeral 10 indicates the shell or casing of the cooler having end plates 11 and 12 secured therein so as to provide a fluid-tight fit within the shell. If desirable, the ends of the shell may be turned in as at 13 to assist in holding the end plates within the shell.

The casing is provided with inlet and outlet ports 14 and 15, respectively, for delivering the fluid which is to be cooled into and out of the container or shell. Means is provided for passing cooling fluid through the shell. This preferably consists of coils 16 and 17, one within the other and attached to headers 18 and 19. Inlet and outlet pipes 20 and 21 connect with the headers 19 and 18, respectively. The end plate 12 also is provided with an exhaust pipe 22 normally closed by a valve. In operation fluid to be cooled is admitted to the port 14. Cooling fluid under pressure is expanded into the pipe 21 and passes through the header 18 into

the coils 16 and 17. The expansion of this fluid from high to low pressure reduces its temperature to a very low degree. The cold fluid within the coils absorbs heat from the fluid to be cooled, which surrounds the coils. When used as a liquid cooling device in the manufacture of carbon dioxide snow, liquid carbon dioxide is reduced to a very low temperature within the shell 10. By having the fluid pass through a relatively large shell the danger of water ice clogging the pipes is removed. As a coolant I preferably use carbon dioxide under pressure. This fluid under pressure is expanded into the inlet pipe 21 during which expansion its temperature is greatly reduced. The pipe 22 is provided for cleaning out the shell in case water ice does become frozen on the sides of the casing or on the cooling coils. This may be done by admitting hot gas to the shell.

While for most uses it may be preferable to pass the fluid to be cooled into a shell and circulate a cooling medium through it, I do not limit myself to this method, as I may pass the fluid to be cooled through pipes or coils within the shell and admit cooling fluid to the shell surrounding the pipes or coils. Furthermore, I do not limit the invention to the use of coils such as shown, or even to coils. Pipes, tubes or other conduits passing through the shell may be substituted, or I may use any fluid transmission means which will act to carry off the heat from the fluid to be cooled.

As stated in the objects of the invention, this device acts to dry a fluid as well as to cool it. By drying it in this sense I mean the removal of water therefrom. When liquid carbon dioxide is reduced to a low temperature any water contained in it is frozen on the coils 16 and 17. From time to time this may be thawed out and drained off through the pipe 24.

It will be obvious to those skilled in the art that various changes may be made in my device without departing from the spirit of the invention, and I therefore do not limit myself to what is shown in the drawing and described in the specification but only as set forth in the appended claim.

Having thus fully described my said invention, what I claim as new and desire to secure by Letters Patent, is:

6 A cooler comprising a casing forming a fluid chamber, inlet and outlet ports to said chamber, a pair of headers in said chamber, said headers being connected by a plurality of nested coils, inlet and outlet pipes connected to said headers, said headers being
10 supported in said casing by said inlet and outlet pipes, and inlet and outlet connections to the interior of said chamber for passing warm fluid through the chamber for thawing out the chamber from time to time, substantially as set forth.

15 In witness whereof, I have hereunto set my hand at Waynesboro, Pennsylvania, this 16th day of Jan., A. D. 1929.

FRANK R. ZUMBRO.
